UNITED STATES PATENT OFFICE.

HYRAM J. BAYARD, OF CHICAGO, ILLINOIS.

RAILWAY-CAR.

SPECIFICATION forming part of Letters Patent No. 772,909, dated October 18, 1904.

Application filed February 13, 1904. Serial No. 193,381. (No model.)

To all whom it may concern:

Be it known that I, HYRAM J. BAYARD, a citizen of the United States of America, and a resident of Chicago, Cook county, Illinois, have invented certain new and useful Improvements in Railway-Cars, of which the following is a specification.

This invention relates to certain improvements in railway-cars, and particularly in that class of such cars which are designed for the transportation of liquid freight; and the object of the invention is to provide a car of this general character of an improved and simplified construction which shall be adapted for carrying solid as well as liquid freight, so as to be better adapted for service than are cars of this kind such as are in general use.

The invention consists in certain novel features of the construction, combination, and arrangement of the several parts of the improved freight-car whereby certain important advantages are attained and the device is rendered simpler, cheaper, and otherwise better adapted and more convenient for use, all as will be hereinafter fully set forth.

The novel features of the invention will be carefully defined in the claims.

In the accompanying drawings, which serve to illustrate my improvements, Figure 1 is a side elevation showing a freight-car constructed according to my invention. Fig. 2 is an enlarged sectional view taken lengthwise and vertically through one end portion of one of the liquid-carrying tanks of the improved car. Fig. 3 is a section taken transversely and vertically across one end portion of the platform of the car, showing the liquid-carrying tanks supported therein. Fig. 4 is a plan view showing one end portion of one of the liquid-carrying tanks and illustrating the means for securing the same in place within the car-platform. Fig. 5 is a sectional detail view taken transversely through the liquid-carrying tank and illustrating certain features of the means for securing the same in place in the car-platform.

As shown in the views, 1 indicates the car-trucks, and 2 the platform, which is constructed with spaced metal strips 9, 9, extended along its lateral and end edges, between which strips

9 are interposed wooden blocks 15, as seen in Figs. 1 and 3, and between the ends of such wooden blocks 15 there are produced sockets 3, adapted to receive stakes or projections 4, extended downward from the lower part of the car-body 5, whereby the said car-body is removably supported on the platform and may be lifted therefrom to permit of using the car as a platform-car or may be replaced by a body of another type suitable for a different kind of freight.

6 indicate liquid-carrying tanks extended lengthwise along opposite sides of the car-platform and embedded therein beneath the flooring, as shown in Figs. 2 and 3, and said tanks have shallow end portions 7 extended within the platform above the car-trucks and deeper central portions, which depend in the space central of the car between said trucks. Each tank 6 is also provided with a filling-inlet 8 at one end of the car, and for the withdrawal of the liquid contents from said tanks there is provided a transverse or horizontal pipe 10, extended across one end of the deeper central portion of each tank and having connection with each tank, as shown in Figs. 1, 2, and 3. In this pipe 10, between the two tanks 6, there is provided a cock or valve 12, and at each end of said pipe there is provided another similar cock or valve 11, and it will be obvious that by proper manipulation of these cocks or valves 11 and 12 the liquid contents of one or both of the tanks 6 may be drawn off. It will also be obvious that when the central cock or valve 12 is opened both tanks may be filled in unison through the inlet 8 of one tank, and when said central cock or valve is closed the tanks may be separately filled, so that a different liquid may be carried in each tank. Each tank 6 is also provided at an end of the car with a vent extended upward through the car-body and opening above the roof of the same for the discharge of fumes and vapors from the contained liquids and for affording proper ventilation and equalization of pressures within the tanks, and such vents comprise nipples 7^a, produced on the upper wall of each tank, as seen in Figs. 2 and 4, in which nipples are to be engaged the projecting lower ends of vent-

pipes 14, extended upward within or adjacent to the end wall of the car-body 5 to the roof thereof and having above said roof an open end surmounted by a cowl or similar device, 5 as shown in Fig. 1. The engagement of the lower end of the vent-pipe 14 within nipple 7^a is detachable, so that when the car-body is lifted off from the platform the said lower end of pipe 14 will be readily withdrawn from said nipple.

The shallow end portions 7 of the tanks 6 are substantially equal in depth to the depth or thickness of the platform 2, so that said end portions 7 of the tanks will be supported 15 in the completed structure upon the cross beams or joists 13 13, commonly provided beneath the platforms of cars, and in order to permit of securely holding the ends of the tanks to the ends of the platform 2 I prefer 20 to cut away the inner strip 9 opposite the end of each tank, as seen in Figs. 2 and 4, and to let such end of the tank into the space between the inner and outer strips 99. I also provide, preferably, a metal plate or stirrup 16, 25 extended beneath the strips 9 and across the under side of the end of the tank, said stirrup being provided with an upturned outer flange 17, riveted or otherwise secured to the outer strip 9 of the platform and being also provided 30 at opposite ends with similar upturned flanges 18 18, riveted or otherwise held to the inner strip 9 at opposite sides of the tank. In this way the tank is securely held at its ends to the framing of the platform, being rested on the 35 stirrup 16, and it will be obvious that this structure greatly stiffens and strengthens the car-platform and permits of dispensing with certain of the longitudinal beams commonly provided in said platform, so that an economy 40 is effected and increased strength attained.

From the above description of my invention it will be apparent that the improved railway-car constructed in accordance therewith is of 45 an extremely simple and inexpensive nature and is of greatly-increased strength, while be-

ing at the same time adapted for the transportation of solid and liquid freight of various kinds, either separately or together, since one kind of liquid freight may be carried in one tank while another kind may be in the other 50 tank, and it will also be obvious from the above description that the device is capable of considerable modification without material departure from the principles and spirit of the invention, and for this reason I do not wish 55 to be understood as limiting myself to the precise form and arrangement of the several parts of the device as herein set forth in carrying out my invention in practice.

Having thus described my invention, what I claim, and desire to secure by Letters Patent, is—

1. A railway-car having a platform provided with a metal frame extended along its ends, a tank extended lengthwise of the platform and stirrups secured to the metal frame at each end of the platform and on which the ends of the tank are rested.

2. A railway-car having a platform, liquid-carrying tanks extended lengthwise of the platform along the opposite sides thereof and provided with inlets, and a discharge-pipe extended along the ends of the tanks and having a connection with each of said tanks and having between its connection with each two 75 tanks, a cock and at each end a cock.

3. A railway-car having a platform, a tank extended beneath the platform and provided with an opening in its top, a car-body removably supported on the platform and a vent-pipe extended up through the car-body with its lower end detachably engaged in the opening in the tank and its upper end open and extended above the car-body.

Signed at Chicago this 16th day of December, 1903.

HYRAM J. BAYARD.
